UNITED STATES PATENT OFFICE

162,847

RADIO CABINET

Ray Kronsberg, Los Angeles, Calif.

Application March 25, 1948, Serial No. 145,335

Term of patent 3½ years

(Cl. D56—4)

To all whom it may concern:

Be it known that I, Ray Kronsberg, a citizen of the United States of America and a resident of Los Angeles, county of Los Angeles, State of California, have invented a new, original, and ornamental Design for a Radio Cabinet, of which the following is a specification, reference being made to the drawing as forming an element thereof.

In the drawing:

Figure 1 is a front perspective view of a radio cabinet showing my new design; and,

Figure 2 is a side elevational view thereof.

The characteristic features of my design reside in the portions shown by means of full lines in the drawing.

I claim:

The ornamental design for a radio cabinet, as shown and described.

RAY KRONBERG.
